US0D1019668S

(12) **United States Design Patent** (10) Patent No.: **US D1,019,668 S**
(45) Date of Patent: ** Mar. 26, 2024

(54) **DATA STORAGE DEVICE**

- (71) Applicant: **Western Digital Technologies, Inc.**,
San Jose, CA (US)
- (72) Inventors: **Derek Niizawa**, Sunnyvale, CA (US);
Minsung Kwon, Palo Alto, CA (US);
Alfonso Calderon, Redwood City, CA
(US)
- (73) Assignee: **Western Digital Technologies, Inc.**,
San Jose, CA (US)
- (**) Term: **15 Years**
- (21) Appl. No.: **29/775,446**
- (22) Filed: **Mar. 23, 2021**

CLAIM

The ornamental design for a data storage device, as shown and described.

DESCRIPTION

FIG. 1 is a front, side, and top isometric view of a data storage device embodying the new design.

FIG. 2 is a cross-section view along lines 2-2 in FIG. 1;

FIG. 3 is a front view thereof;

FIG. 4 is a rear view thereof;

FIG. 5 is a first side view thereof;

FIG. 6 is a second side view thereof;

FIG. 7 is a top view thereof; and,

FIG. 8 is a bottom view thereof.

The broken lines in the drawings depict portions of the data storage device that form no part of the claimed design.

1 Claim, 8 Drawing Sheets
